APPARATUS FOR USE IN COVERING HEELS

John C. Shambow, Boston, Mass., assignor to
United Shoe Machinery Corporation, Paterson,
N. J., a corporation of New Jersey

Application March 23, 1933, Serial No. 662,324

4 Claims. (Cl. 12—122)

This invention relates to improvements in apparatus for use in covering heels.

In covering wood heels it is customary for a single operative first to apply cement to all the 5 heels and covers of a large number of heel-and-cover lots and to set the cemented heels and covers aside to allow the cement to become tacky so that the covers will properly adhere to the heels and thereafter to pull the covers on the 10 heels leaving the cover margins projecting beyond the attaching, the top-lift-receiving and the breast faces of the heels, and as each heel is covered to finish the heel by trimming and snipping the projecting cover margins and pressing them 15 down against the work. This mode of operation results in the use of a large amount of bench or rack space in the heel-covering plant for holding the cemented heels and covers, and, moreover, since the finishing operations above referred to 20 take approximately twice as long as either the cementing or the pulling-on operations, large quantities of heels and covers are forced to remain idle for a much longer period of time than required for proper conditioning of the cement 25 and consequently the progress of the work through the factory is unnecessarily delayed.

In view of the foregoing, one object of the present invention is to provide an improved heel-covering stand, the use of which will facilitate the 30 operations of pulling on heel covers and trimming, snipping and tucking down the cover margins, and which will assist in eliminating the disadvantages above referred to with reference to delays in the performance of the heel-covering 35 operations by the methods heretofore generally practiced.

To the accomplishment of this object one feature of the present invention consists in the provision of a covering stand which, as herein illustrated, comprises a heel clamping jack for use 40 in pulling covers on heels, and a work bench having a front portion supporting said jack and shaped at the opposite sides of the jack to afford clearance for the arms of an operator using 45 the jack, said bench having a rear portion of a construction providing a support located within arm's reach of the operative of the jack for receiving 50 covered heels and providing also bench spaces for the use of two finishing operatives stationed 55 one at each side of the bench and within arm's reach of said support.

The illustrated bench is provided with two racks which are located at opposite sides of the jack, one of the racks being adapted to hold a tray of cemented heels at the level of the bench and within

convenient arm's reach of the operative of the jack while the other rack is adapted to hold three trays of cemented heel covers also within convenient arm's reach of the operative of the jack, the trays of covers being supported one above the other, with the lowermost tray at the level of the bench. At the rear of the bench, between the portions used by the finishing operatives, the bench is bifurcated or cut away to permit finished 5 heels to be dropped through a central opening 10 into a box suitably positioned upon a support beneath the bench, and two counting devices are or may be located just above the opening in the bench, one counting device for each finishing 15 operative, for counting the finished heels as they are being dropped into the box.

The invention further consists in the features of construction and combinations and arrangements of parts hereinafter described and claimed, the advantages of which will be apparent to those skilled in the art.

The invention will now be explained with reference to the accompanying drawings, in which

Fig. 1 is a perspective view of my improved covering stand;

Fig. 2 is an elevational view of the left-hand side of the covering stand, portions thereof being broken away to disclose certain structural features;

Fig. 3 is a fragmentary top plan view of the 30 covering stand showing a tray of heels and trays of covers located in their respective positions on the stand; and

Fig. 4 is a detailed sectional view taken substantially along the line IV—IV of Fig. 1.

Referring to the drawings, the covering stand consists of a unitary metallic structure comprising, in general, a work bench 10, a rack 12 which is located at the left-hand side of the bench, and a rack 14 which is located at the right-hand side 40 of the bench. The bench 10 is supported upon four legs 16 at a convenient height for use by operatives seated around the bench. The front of the bench is formed with a relatively narrow, forwardly projecting portion 18 upon which is 45 mounted a heel clamping jack 20 for holding a heel, such as the heel A (Fig. 2) while a cover is being pulled thereon by a covering operative seated in front of the jack at what may be termed a covering station B. Immediately behind the 50 narrow projecting portion 18 of the bench the lateral edges of the bench diverge rearwardly, as indicated at 22. Thus the portion of the bench which supports the jack 20 is shaped to provide ample arm and elbow room for an operative using 55

the jack and in that way to facilitate the operation of clamping a heel and pulling a cover thereon. The jack 20, as best shown in Fig. 2, comprises a C-shaped frame 26 which is rigidly secured to the bench and which carries an adjustable upper clamping member 28 for engaging the top-lift-receiving face of a heel. Cooperating with the upper clamping member 28 in clamping a heel is a movable lower clamp member 32 which is adapted to engage the attaching face of the heel. The lower clamp member 32 is pivoted at 34 to the frame 26 and is formed with a rearward extension 36 which is connected by means of a rod 38 with a foot treadle 40 which is pivoted to a floor bracket 42. A spring 44 attached to the rear extension of the lower clamp member 32 tends to hold the clamp normally in open position, the arrangement being such that depression of the treadle 40 will operate the clamp to hold a heel firmly in the position shown in Fig. 2. The construction and mode of operation of the jack itself, however, is similar to that of jacks customarily employed by wood heel covering operatives.

25 The rack 12 is adapted to receive a tray of heels to be covered, such for example as the tray C (Fig. 4), and to support the tray in a horizontal position at the level of the work bench and conveniently close to the jack 20, elbow room for the operative, however, being provided between the forward extension 18 of the bench 10 and the tray C. The illustrated rack 12 consists of a skeleton shelf formed of a U-shaped strip 46 the opposite ends of which are secured to angle irons 48 carried by a horizontal bar 50 which, in turn, is secured to one of the diverging edges 22 at the left-hand side of the bench 10. As shown, the strip 46 is rigidly supported by means of a brace 52 secured at one end to the middle of the strip 46 and at the opposite end to one of the legs 16. The rack 12 is particularly designed for supporting and positioning a heel tray or screen of a construction substantially like that of the illustrated tray C. As shown in detail in Figs. 3 and 4, the bottom of the tray C is set in a thin rectangular frame C' which constitutes the rim of the tray. To insure that the tray C shall be firmly held and positively located in a predetermined angular position with respect to the bench 10 the angle irons 48 and the bar 50 are constructed and relatively arranged to afford a channel-like holder for receiving one end portion of the frame or rim C' of the heel tray so that when the tray is placed with the bottom of the tray resting upon the strip 46 one end of the frame C' will be confined within the channel above referred to and the tray will be positioned as shown in Fig. 4. When thus positioned, displacement of the tray in a direction away from an operative at the covering station B is prevented by means of a stop 58 formed by bending outwardly the rear extremity of the bar 50 and displacement of the tray in the opposite direction is prevented by engagement of the front edge of the tray with the forwardly projecting portion 18 of the bench. The bar 50 and the angle irons 48, by engaging opposite sides of the end portion of the frame C', serve to prevent displacement of the tray in directions toward and away from the sloping edge 22 of the bench. Thus the tray is definitely positioned in a predetermined angular relation of substantially 45° with respect to the front of the work bench. As shown, the tray C is located within convenient arm's reach of the operative at the

covering station B so as to facilitate transfer of heels from the tray C to the jack 20.

The rack 14 is adapted to provide support for three heel cover trays, such as the trays indicated at D in Figs. 2 and 4, the construction of 5 the rack being such that the trays are supported in horizontal planes located one above the other with ample clearance space between them and with the lowermost tray disposed substantially at the level of the work bench and spaced away from 10 the projecting portion 18 of the bench and the adjacent edge 22 to afford elbow room for the covering operative. As shown, the rack 12 comprises a lower skeleton frame or shelf 62 which, as best shown in Fig. 1, is constructed of angle 15 bars riveted together at their ends so as to form a rectangular frame. The illustrated shelf 62 is supported by means of four legs 64 and is rigidly secured to the bench 10 by means of a bracket 66, the latter being so located as not to interfere 20 with the actions of the covering operative in transferring covers from the cover trays to the jack and pulling on the covers. Two of the legs 64 of the rack 12 are disposed at the rear of the frame 62 and are extended upwardly, as shown at 25 68, to provide support for the two upper shelves 70 and 72 of the rack, each of which, as shown, is formed of a U-shaped strip the opposite ends of which are riveted to the upward extensions 68 of the rear legs 64 and are rigidly supported by 30 means of braces 74. A brace 76 is secured at its upper end to one of the rear legs 64 and is adapted to be secured at its lower end to the floor so as to be more rigidly to support the rack 14 in order to prevent undesired vibration thereof. As shown, 35 the lower shelf 62 is wider than the upper shelves 70 and 72, the lower shelf being extended toward the bench 10 to enable the lower tray to be pulled toward the jack by the covering operative as may be desirable to afford better access to the covers 40 lying upon the right-hand portion of the tray.

Upon the work bench 10 at the rear of the jack 20, as best shown in Fig. 4, is provided bench space 78 for receiving heels upon which the covers have been pulled by the operative at the covering 45 station B. This bench space 78 which constitutes a receiving support for the covered heels is located within convenient arm's reach of the covering operative. As each heel is covered, the covering operative removes it from the jack and places 50 it upon the receiving support 78, where the heels may accumulate in a pile, as indicated at E in Fig. 3. The work bench 10 is adapted to afford at opposite sides of its rear portion ample bench spaces or working areas 80 and 82 for two finishing 55 operatives (located at two finishing stations designated respectively F and G) who are to perform the operations of trimming, snipping, and pressing down the cover margins which project beyond the heels after the covers have been pulled thereon. Between the working areas 80 and 82 at the rear of the work bench 10 the bench is bifurcated or cut away, as indicated at 84, to receive two counting devices 86 and 88 for use by the finishing 60 operatives at stations F and G, respectively, in 65 counting the finished heels as the latter are dropped through the counting devices into a suitable container such as the box H. The opening or cut-away portion 84 serves also to separate the areas 80 and 82 to avoid interference between the 70 operations performed by one finishing operative and those performed by the other finishing operative. The separate counting devices 86 and 88 afford means for comparing the amount of work 75 accomplished by the two finishing operatives and

also for checking the quantities of heels in the different lots with the quantities specified by order tags one of which accompanies each lot of heels. The two counting devices 86 and 88 are 5 similar in construction and each embodies features which are described and claimed in United States Letters Patent No. 2,015,147, granted September 24, 1935, upon application of R. F. Knight. The box H is supported by two 10 spaced angle-iron guides or supports 90, the box being introduced from the rear of the stand and slid forwardly along the guides 90 until its forward end engages abutments 92 which are secured to the guides 90 and which locate the box in position 15 to receive the heels. The guides 90 and the abutments 92 are made adjustable to accommodate boxes of different sizes. As shown, each guide 90 consists of an angle iron strip the ends of which rest upon horizontal crossbars 94 that 20 are secured to the legs 16 and serve also as braces for the legs. The guides 90 are secured to the crossbars 94 by means of bolts 96 and a plurality of bolt-receiving holes 98 are provided in each crossbar to enable the guides to be adjusted to 25 accommodate heel boxes of different widths. The abutments 92 are secured by bolts 100 to the guides 90, a plurality of holes 102 in each guide permitting the abutments to be adjusted lengthwise of the guides to accommodate heel boxes of different lengths. A cement cup 106 secured to the 30 bench 10, in front of the counting devices 86 and 88, is adapted to contain liquid latex for use by the finishing operatives, if necessary, to insure proper adherence of the cover margins to the 35 wood when they are pressed down.

It would be apparent from the above description that the construction of the parts constituting the covering stand is such as to enable a team of three operatives to operate in an efficient and 40 expeditious manner to pull covers on successive lots of heels, to perform the necessary trimming, snipping and pressing down operations upon the margins of the attached covers, to count the finished heels, and to deliver the successive lots 45 into separate receptacles ready for attachment to corresponding lots of shoes. Moreover, the construction of the stand and the arrangement of its component parts is such that all the above-mentioned operations may be performed and the heels 50 transferred from the covering operative to the finishing operatives, without the necessity of any operative leaving her respective working station.

Having described my invention, what I claim as new and desire to secure by Letters Patent of the 55 United States is:

1. A heel covering stand comprising a heel

clamping jack for use in pulling covers on heels, and a work bench having a front portion supporting said jack and shaped at the opposite sides of the jack to afford clearance for the arms of an operator using the jack, said bench having a rear 5 portion of a construction providing a support located within arm's reach of the operative of the jack for receiving covered heels and providing also bench spaces for the use of two finishing operatives stationed one at each side of the bench 10 and within arm's reach of said support, said bench spaces being separated by a heel-receiving opening in the bench.

2. A heel covering stand comprising a heel clamping jack for use in pulling covers on heels, 15 and a work bench having a forwardly projecting, relatively narrow portion upon which said jack is mounted and a bifurcated rear portion providing separated working areas at opposite sides of the bench for the use of two finishing 20 operatives and an opening between said areas for receiving finished heels.

3. A heel covering stand comprising a work bench having a relatively narrow, forwardly projecting portion supporting a heel clamping jack 25 and a relatively large rear portion shaped to provide a support located within arm's reach of an operative using said jack for receiving covered heels, said support being formed with separated bench spaces located adjacent to the opposite 30 sides of the bench for the use of two finishing operatives and the working surface of the bench being extended at opposite sides of the jack but in spaced relation thereto and within arm's reach 35 of the operator thereof, thus providing for the support of heels and heel covers to be operated upon in positions to be easily transferred to the jack but without interfering with the operation of the jack.

4. A heel covering stand comprising a work 40 bench having a forwardly projecting relatively narrow portion for use by a heel covering operative, a relatively wide rear portion for use by a plurality of finishing operatives, and a portion extending laterally from said forwardly projecting portion for supporting a heel tray having a downwardly projecting rim, there being a narrow channel formed between said forwardly projecting and said laterally extending portions and arranged to receive and confine the rim of said tray 45 to retain the tray against edgewise displacement in a predetermined position relatively to the forward and rear portions of the bench thereby to facilitate the performance of the heel covering 50 and finishing operations. 55

JOHN C. SHAMBOW.
